UNITED STATES PATENT OFFICE.

CARL WINTERLING, OF FRANKFORT-ON-THE-MAIN, GERMANY.

SYLLABLE-WRITING MACHINE.

988,160.

Specification of Letters Patent. Patented Mar. 28, 1911.

Application filed January 24, 1911. Serial No. 604,342.

To all whom it may concern:

Be it known that I, CARL WINTERLING, a subject of the German Emperor, and residing at Frankfort-on-the-Main, Germany, ⁵ have invented new and useful Improvements in Syllable-Writing Machines; and I do hereby declare the following to be a full, clear, and exact description of the same.

This present invention relates to syllable-writing machines and has for its object to provide an improved arrangement of type-bars and key-levers, wherein the keys are arranged in rows placed one behind the other, while the type-bars are arranged vertically on a circular line around the printing point on the platen. In order to enable syllables to be written on this machine, the type-bars placed at opposite sides of the machine and outside the side of the bars ¹⁰ with single types, are provided with syllables and carry extensions which act on universal rails arranged concentrically to the printing point and acting on the escapement of the carriage. Arranged in front ¹⁵ of the usual keys for the single type-bars are rows of keys for the syllable bars, these keys being connected with the corresponding syllable-bars through the agency of horizontal traction-rods. This arrangement and ²⁰ connection enable syllables to be written, without the dimensions and shape of the machine being different from the usual type-writing machines with single types.

Each writer who uses a syllable-writing ²⁵ machine of this invention works on a well-known key-board and therefore he will learn the use of the syllable-keys much more quickly than if he were to learn the art from the beginning. The machine operates ³⁰ in such a way that single characters and syllables may be written as desired. The keys for the single characters operate in the well-known manner, while by the depression of the keys for syllables the respective syllables are printed and the carriage is simultaneously moved to the left to an extent corresponding to the respective number of characters. For instance the word "to-get-her" ³⁵ (together) will be written by depressing one syllable-key with two characters ("to") and two syllable-keys with three characters ("get" and "her"), while the word "ma-⁴⁰ ch-in-e" (machine) will be written by depressing three syllable-keys with two characters ("ma", "ch" and "in") and a single

type-key ("e"). These words may also be written as usual by means of single type-keys.

My invention will be readily understood from the following description taken in connection with the accompanying drawings, ⁶⁰ wherein—

Figure 1 is a vertical longitudinal sectional elevation of the complete machine with the escapement of the carriage and ⁶⁵ ribbon mechanism omitted; Fig. 2 is a top plan view, showing at the right hand side the diagrammatical connections between the keys and type-bars; Fig. 3 is a diagrammatical side elevation showing the mechanism of the key-levers; Figs. 4 and 5 show a side elevation and top plan view respectively of adjustable bearings; Fig. 6 shows the device for guiding the type-heads near the printing point; Fig. 7 is a type with ⁷⁰ three characters; Fig. 8 is a type with two characters; Fig. 9 shows detail views of a type-head; Fig. 10 is a detail view of a type-bar; Fig. 11 is a detail view of a connecting link. ⁷⁵

The type-bars 14 are journaled on shafts ⁸⁰ 16 or 16^a carried by supports 2 or 2^a respectively, provided with slots 15 or 15^a in which the type-bars are guided. Connected with the arm 17 of each type-bar 14 is a link 18, ⁸⁵ in connection with the sub-lever 19, arranged in a slot 20 of the plate 3 and connected with the traction-rod 21, extending downwardly and pivotally connected at its lower end with the bell-crank lever 22. The latter is connected with a traction-rod 23, connected at its opposite end with another bell-crank lever 24, with which is connected the shank 25 of the key 26. The bell-crank levers 22 are journaled in slotted bearings 27^a provided ⁹⁰ with a cylindrical pivot-pin 28 (Figs. 4 and 5) extending through a plate 6 and held rotatably in the latter by means of a screw 29 screwed into said pivot-pin. This arrangement enables the slotted bearings to be ⁹⁵ adjusted in the direction of the movement transmitted to the levers 22 journaled in said bearings. The plate 6 is cut away on a semi-circular line like the type-bar supports and has holes 6^a (Fig. 1) through which extend ¹⁰⁰ the rods 21. The bell-crank levers 24 are journaled in a similar way, except that they are arranged on the cross-rails 7 below the key-board. The key-shanks 25 which are pivotally connected with the bell-crank le- ¹⁰⁵ 110

vers 24 are guided on cross-rails 8 and preferably made of thin tubes. Each key 26 is provided with a reduced extension 30 extending into the corresponding shank 25. 5 In order to hold these parts in the position of rest or to bring the key-lever back in its position of rest after it has been depressed, I have provided a pushing spring 31 acting on the sub-lever 19, which latter is provided 10 with a boss 19^a (Fig. 11) to prevent the spring 31 from slipping off the sub-lever. The tension of spring 31 may be adjusted in any well-known manner, the drawings showing, somewhat diagrammatically, a common 15 form of structure for this purpose, 32 indicating an adjusting screw carried by the plate 4.

In order to enable the keys to operate in a perfect manner, it is necessary that the key 20 be moved very easily through the first half of its depression, while for the second half a higher resistance must be overcome because then the momentum assists in overcoming this increased resistance. To this end, the 25 sub-lever 19 has a rounded projection 34 arranged to rest or bear on the smooth surface of the plate 3 and roll on the same when the sub-lever is moved from its position when at rest (Fig. 11). Owing to this arrangement 30 the length of the two arms A, B of the sub-lever 19 will be varied, so that the motive force first acts on the long arm B, the sub-lever 19 then rolling with its rounded projection on the plate 3 whereby the arm B 35 will be progressively shortened. By this arrangement, the type-bar will be moved more quickly as it comes near the platen, so that the work may be written much more quickly. Extending through an oblong hole 35 of the 40 sub-lever 19 is a shaft 36 which holds the sub-lever 19 from endwise movement in its slot 20, but permits the rocking movement of the lever as described.

In order to obtain a compact construction, 45 the type-heads or types having single characters are carried by the type-bars located in the middle of the semi-circle, while the type-heads with syllables are carried by the type-bars located on the sides thereof. I have arranged two rows of sub-levers 19 of different 50 length, thereby enabling said sub-levers to be journaled on a single shaft; the bell-crank levers 22 are arranged accordingly (Fig. 1), that is, these levers are intentionally arranged 55 one behind the other and not side by side, in order to permit the same to be connected with the sub-levers 19 by approximately vertical connections and to reduce the width of the frame and obtain a compact 60 construction.

The type-bars are provided with lugs or 65 projections 37, 37^a and 37^b (Fig. 10). The lug 37 serves to depress the universal rail 9 whereby the carriage escapement is moved, 70 and for this reason this lug is provided on

all type-bars. The universal rails are arranged in such a way that by the simultaneous depression of the rails 9 and 9^a the carriage is moved to the extent of one character. When the rails 9 and 9^b are depressed simultaneously, 75 the carriage is moved to the extent of two characters, and when the rail 9 is depressed alone, the carriage is moved to the extent of three characters. The lugs 37^a and 37^b are arranged in such a way that all 75 type-bars carrying a type having a single character are provided with a projection 37^a. The type-bars which carry a type having two characters (syllable-types) are provided with a projection 37^b while the type-bars 80 carrying a type having three characters, omit both projections 37^a and 37^b.

Arranged close to the printing point 8 is a head-guide 10 provided with a cross-shaped opening (Fig. 6). The opening 38 85 serves to guide the types having single characters, while the opening 39 serves to guide the syllable types. This head-guide requires the types to be movably secured to the type-bars. 90

Secured to the upper end of each type-bar 14 are two strips or plates 41, between which is held the type-head (Fig. 10). The latter is pivoted at 44 while the oblong hole 45 (Fig. 9) through which extends a rivet 95 46 permits the head to be moved laterally to a certain extent. This arrangement enables the character to be printed perfectly, as the lateral movement of the type-head is limited by the head-guide near the printing 100 point and the type-head is prevented from tilting because the fulcrum 44 is located in the middle of the type-head. The type-body 42 is held in the type-head 40 by means of its beveled pin or shank 43, whereby the 105 type may be accurately adjusted according to the location of the type-bar.

Arranged below the universal key-board, that is the four upper rows of keys, is a second spacing key 47. If the hand of the 110 writer has actuated one of the upper keys for writing the last character of a word, it is not necessary for it to cross the whole key-board for actuating the usual spacing-key 48, as it may actuate the spacing-key 47 115 located in the middle of the key-board. This arrangement avoids an objection which is particularly found in so-called full key-board machines.

As shown in Fig. 2, the keys are connected 120 with the corresponding type-bars by means of horizontal traction-rods, the rods 23 of the keys for single characters crossing the rods of the keys for syllables. This arrangement is permitted by the step-like arrangement of the bell-crank levers 22 and 24. The latter are adjusted in such a way that the bell-crank levers of each separate pair of levers are in line with each other, the traction-rod 23 extending in the middle below 125 130

the key-head corresponding to this pair of bell-crank levers, so that a straight connection is obtained.

The spacing-keys 47 and 48 are connected by means of a rod 49 with the feed and escapement of the carriage. Fig. 2 shows the arrangement of a line-lock key 50.

When at rest the type-bars are held in place by the abutment 5. The type-bars are protected against injury by a casing 12, 13.

Having fully described my invention, what I claim and desire to secure by Letters Patent is:—

1. In bar mechanism for typewriting machines, a type-basket having a plurality of type-bars, and a key for and operatively connected to each bar, said bars and keys each being arranged in series, one series of keys extending substantially the full width 20 of the key-board, the corresponding series of bars being positioned at an intermediate portion of the type-basket.
2. In bar mechanism for typewriting machines, a type-basket having a plurality of 25 type-bars, and a key for and operatively connected to each bar, said bars and keys each being arranged in series, one series of keys extending substantially the full width of the key-board, the corresponding series 30 of bars being positioned at an intermediate portion of the type-basket, and another series of keys and bars having their connections extending angularly with respect to the connections of the first-named series.
3. In bar mechanism for typewriting machines, a type-basket having a plurality of type-bars, and a key for and operatively connected to each bar, said bars and keys each being arranged in series, one series of 40 keys extending substantially the full width of the key-board, the corresponding series of bars being positioned at an intermediate portion of the type-basket, and a second series of bars positioned at one end of the first-named series, the keys for the second series 45 of bars being positioned in substantial parallelism with the keys of the first series, the connections of the second series crossing the planes of the connections of the first series.
4. In bar mechanism for typewriting machines, a type-basket arranged segmentally and including a plurality of type-bars arranged in successive series in the direction of length of the basket, and a key for and 50 operatively connected to each bar, the keys for each series being adjacent to each other in the key-board, the operating connections between key and bar of one series crossing the planes of similar connections of a different series.

5. In bar mechanism for syllable-writing typewriting machines, a type-basket having a plurality of series of type bars, one series having single-character types and another 55 series having plural-character types, the

single-character type-bar series being positioned at an intermediate portion of the type-basket.

6. In bar mechanism for syllable-writing typewriting machines, a type-basket having 70 a plurality of series of type bars, one series having single-character types and another series having plural-character types adapted to print simultaneously, the single-character type-bar series being positioned at an intermediate portion of the type-basket. 75

7. In bar mechanism for syllable-writing typewriting machines, a type-basket having a plurality of series of type-bars, one series having single-character types and another 80 series having plural-character types, the single-character type-bar series being positioned at an intermediate portion of the type-basket, and a key for each type-bar, said keys being also arranged in series in 85 the key-board, with the keys of the single-character series extending substantially the full width of the key-board.

8. In bar mechanism for syllable-writing typewriting machines, a type-basket having 90 a plurality of series of type bars, one series having single-character types and another series having plural-character types, the single-character type-bar series being positioned at an intermediate portion of the 95 type-basket, and a key for each type-bar, said keys being also arranged in series in the key-board, with the keys of the single-character series extending substantially the full width of the key-board, said series being 100 positioned intermediate the type-basket and the remaining series of keys.

9. In bar mechanism for typewriting machines, a type-bar, a key therefor, and connections between the bar and key, said connections including a sub-lever supported intermediate its ends and connected to its support to hold the lever against endwise movement, said lever having a curved face adapted to co-act with said support to provide a 110 variable fulcrum in advance of the point of connection of lever and support.

10. In bar mechanism for typewriting machines, a type-bar, a key therefor, and connections between the bar and key, said connections including a sub-lever having an elongated slot extending transversely of the lever and adapted to receive a support-carried securing member, the slot and member preventing relative endwise movement of the lever and its support, said lever having a curved face adapted to co-act with said support to provide a variable fulcrum in advance of said transverse slot. 120

11. In bar mechanism for typewriting machines, a plurality of type-bars, a key for each bar, connections between the key and its type-bar, said connections including a sub-lever, said sub-levers being of more than a single series, the levers of each series being 130

of equal length and differing in length from the levers of the remaining series, and supporting means to which the sub-levers are connected and on which they are pivotally supported, the point of connection of the respective levers being on a substantially symmetrical line, each lever projecting on opposite sides of said line, the amount of projection being proportionately the same in all 10 of the levers.

12. In bar mechanism for typewriting machines, a plurality of type-bars, a key for each bar, connections between the key and its type-bar, said connections including a 15 sub-lever, said sub-levers being of more than a single series, the levers of each series being of equal length and differing in length from the levers of the remaining series, and supporting means to which the sub-levers 20 are connected and on which they are pivotally supported, the point of connection of the respective levers being on a substantially symmetrical line, each lever projecting on opposite sides of said line, the amount of 25 projection being proportionately the same in all of the levers, adjacent levers of one series being separated by one or more levers of a different series.

13. In bar mechanism for type-writing machines, a plurality of type-bars, a key for each bar, connections between the key and its type-bar, said connections including a

sub-lever, a bell-crank-lever and a link between the sub-lever and bell-crank lever, said sub-levers being of more than a single 35 series, with the levers of each series of equal length and differing in length from the levers of the remaining series, and supporting means to which the sub-levers are connected and on which they are pivotally supported, the point of connection of the respective levers being on a substantially symmetrical line, each lever projecting on opposite sides of said line, the amount of projection being proportionately the same in 45 all of the sub-levers, adjacent sub-levers of one series being separated by one or more levers of a different series, the bell-crank lever of a sub-lever of one series being positioned in advance of a bell-crank lever of a 50 different sub-lever series.

14. In a type-writing machine, the combination of a type-bar having a plurality of projections intermediate its ends, with a plurality of separate universal bars adapted to 55 be engaged by certain of said projections to operate the feed mechanism.

In testimony whereof, I have signed my name to this specification in the presence of two subscribing witnesses.
